[57] CLAIM

The ornamental design for a wooden basket, as shown and described.

DESCRIPTION

FIG. 1 is a perspective view of the wooden basket showing our design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is left side elevation view thereof; and,

FIG. 8 is a perspective view of an alternate embodiment of FIG. 1. The side, top and bottom views not shown of FIG. 8 are identical to the first embodiment except for the color contrast.
